WELL PLUNGER PACKING

Application filed June 21, 1929. Serial No. 372,713.

My invention relates to deep well plungers and more particularly to an improved packing therefor.

An object of the present invention is to provide a well plunger packing embodying a circumferentially yieldable sleeve or liner through which the plunger passes and is actuated to effect a seal by the hydrostatic pressure or liquid column in the well tubing or working barrel.

Further the invention provides a plunger packing wherein the sleeve is arranged to be expanded against the walls of the well tubing or working barrel to effect the seal or contracted about the well plunger, the expansion or contraction being entirely automatic by the column of liquid being raised.

The invention also provides a packing embodying a pair of concentric sleeves having slits therein to render the sleeve highly resilient so that they will expand or contract and arranged in their slits out of registration. Thus the walls of one sleeve will seal the slits of the other to prevent the passage of liquid transversely through the sleeves.

Still another object of the invention is to provide a self adjusting packing which is always held tightly against a metallic surface with which it cooperates and thereby compensates for wear of the latter.

More specifically the invention embraces a yieldable packing sleeve which extends substantially the entire length of the plunger and having a novel arrangement of slits extending longitudinally of the sleeve to render the latter highly resilient and obviating continuing passages through which liquid may drain back into the well in the event that an area of the sleeve becomes worn to such an extent as not to effect a liquid seal.

With the preceding and other objects and advantages in mind, the invention consists in the novel combination of elements, constructions and arrangements of parts and operations to be hereinafter more fully described, claimed and illustrated in the accompanying drawings, wherein:

Figure 1 is a vertical sectional view of a well tubing having my invention in operative position thereon;

Fig. 2 is an enlarged fragmentary longitudinal section of the invention in the well tubing;

Fig. 3 is a similar view showing the upper portion of the invention;

Fig. 4 is a transverse section taken on line 4-4 of Fig. 2;

Fig. 5 is a fragmentary longitudinal section of a modification of the invention in operative position in the well tubing;

Fig. 6 is a transverse section on line 6-6 of Fig. 5; and

Fig. 7 is a transverse section of another modification of the packing.

Referring to the embodiment of the invention disclosed in Figs. 1 to 4 inclusive, a hollow well plunger pump 5 is provided for reciprocation in the usual working barrel or well tubing 6. An exteriorly threaded collar 7 is threaded upon the lower end of the plunger and is formed with a nut 8 for the purpose of removing or applying the collar to the plunger.

A packing is provided for preventing the raised liquid from flowing back into the well which is expanded to tightly engage the walls of the working barrel by the weight of the raised liquid column. This packing consists of an outer resilient sleeve 9 and an inner resilient sleeve 10 formed of sheet metal having high anti-frictional qualities. The sleeve 9 is of such external diameter as to have a free sliding fit within the working barrel and has a substantially greater cross-sectional thickness than the inner sleeve 10 as particularly illustrated in Fig. 4. It will also be observed that the combined cross-sectional thickness of the two sleeves is such as to leave a considerable space between the interior of the sleeve 10 and the exterior of the plunger.

The upper end of the two sleeves are connected together by spot welding or any other convenient manner as indicated at 11. The lower end of the inner sleeve 10 stops short of the lower end of the sleeve 9 and is welded or otherwise secured to the sleeve 9 as indicated at 12. Interior screw threads 13 are provided in the lower end of the sleeve 9 which are threadedly engaged with the

threaded collar 7 to secure the packing to the well plunger.

To render the sleeves highly resilient so that they will be responsive to the hydrostatic pressure of the raised liquid they are provided with rows of spaced longitudinally aligned slits 14. As particularly illustrated in Fig. 1 the slits are arranged in staggered relation around the sleeve so that all areas of the latter will be resilient. In other words the slits are arranged so that there will be no portion of the sleeves free from slits except the end portions of the outer sleeve 9. Thus all areas of the sleeves are free to expand under the influence of the hydrostatic pressure. Moreover by interrupting or spacing the slits of each row liquid is prevented from passing downwardly between the packing and working barrel. That is to say, if the slots 14 were continuous or uninterrupted liquid would have a tendency to flow downwardly through the slits and pass back into the well.

The inner sleeve 10 serves to prevent flow of liquid through the slots in the outer sleeve 9 and for this purpose the slots 14 of the inner sleeve are located between each two adjacent rows of slots in the outer sleeve so that a longitudinal section of the inner sleeve will bridge each row of slots in the outer sleeve. As disclosed in Figs. 2 and 3 the end slots 14 of the inner sleeve 10 extend through the ends of the sleeve so as to increase the flexibility of the packing at this point. However, the ends of the outer sleeve 9 are unbroken or solid.

From the description thus far given it follows that oil or other liquid pumped through the plunger 5 and building up within the working barrel above the plunger likewise builds up between the exterior of the plunger and interior of the packing. The weight or hydrostatic pressure of the liquid therefore expands the packing against the working barrel and produces a liquid seal between the working barrel and the plunger. By reason of this expansion of the packing the liquid seal is maintained at all times regardless of the wear on the interior of the working barrel or the exterior of the packing. In this connection it will be manifest that my invention can be readily utilized in working barrels now in operation and thereby does away with the costly expedient of installing oversized plungers and cups.

In the modification disclosed in Figs. 5 and 6 the hydrostatic pressure is utilized to contract the packing about the plunger. In this instance a bushing 15 having an enlarged upper end 16 which engages an internal seat 17 in the working barrel 6 is provided.

A central guide opening 18 is formed in the bushing through which the plunger 5 operates, the latter having a thimble 19 threaded upon its lower end which prevents

the plunger from being withdrawn from the bushing. A relatively thick inner sleeve 20 having a slightly greater internal diameter than the external diameter of the plunger is received on the latter and has its lower end threaded into the upper end of the opening 18 as at 21. An outer sleeve 22 of materially less cross-sectional thickness than the sleeve 20 is snugly received on the latter and has its ends welded or otherwise secured to the sleeve 20 as at 23. The sleeves are rendered resilient through the instrumentality of the slits 14 above set forth.

In the operation of this embodiment of the invention the liquid confined between the working barrel 6 and packing above the bushing 15 exerts radial pressure upon the packing in an inward direction which causes the inner sleeve 20 to contract against the exterior of the plunger.

In the modification disclosed in Fig. 7 the packing is formed from a single length of sheet metal 24. In this construction the length of sheet metal is wound upon itself to provide an inner sleeve 25 and an outer sleeve 26, the ends of the sheet are feathered or tapered as at 27 so that the inner surface of the sleeve 25 and the outer surface of the sleeve 26 will be truly concentric. To hold the parts together, the longitudinal edges of the sheet are spot welded or otherwise suitably secured to the opposite faces of the sheet. As in the other embodiments of the invention the slots 14 of the two sleeves are disposed in non-registering position and in the manufacture of the device the slits will be stamped in the sheet prior to winding the latter in tubular formation.

From the disclosure it will be manifest that I have provided an all metal packing for a well plunger which depends upon the hydrostatic pressure in the working barrel to effect a liquid tight seal around the plunger. Thus the invention does away with the oversized pistons and cups now employed, and is advantageous over those devices depending upon their inherent resiliency in that a positive seal is had by reason of the hydrostatic pressure operating on the resilient sleeve.

What is claimed is:

1. In combination a well plunger, a pair of concentric metallic packing sleeves encircling the plunger and having their upper ends open and their lower end closed, each of the sleeves having rows of non-communicating slits to render the sleeves resilient whereby hydrostatic pressure in the working barrel in which the plunger is operating will at all times distort the sleeves circumferentially to effect a seal around the plunger.

2. In a well plunger packing a collar to be attached to the lower end of a well plunger, an expandable metallic sleeve to be received on the plunger and having one end attached to the collar and closed by the latter and hav-

ing its upper end open so that liquid in the working barrel will enter between the sleeve and plunger and at all times expand the sleeve against the walls of the working barrel.

5. In combination, a well plunger, a collar attached to the lower end thereof, a metallic expandible sleeve encircling the plunger in spaced relation thereto and having its lower end attached to the collar and closed by the latter so that a column of liquid will always be maintained between the plunger and the sleeve to at all times expand the same against the walls of the working barrel.

10. In combination a well plunger, a pair of concentric metallic packing sleeves encircling the plunger, each of the sleeves being provided with non-registering slits to render them resilient, the inner sleeve being spaced from the plunger, and the outer sleeve having sliding fit within the working barrel in which the plunger is operating, and means for closing the lower ends of the sleeves so that liquid in the working barrel will at all times exert radial pressure on the inner sleeve to force the outer sleeve into liquid tight engagement with the walls of the working barrel.
